UNITED STATES PATENT OFFICE

HARRY G. FISHER, OF DAYTON, OHIO, ASSIGNOR TO DELCO-LIGHT COMPANY, OF DAYTON, OHIO, A CORPORATION OF DELAWARE

WATER PUMP

Application filed January 31, 1927. Serial No. 164,716.

This invention relates to improvements in mounting devices and particularly to such devices used in connection with water supply systems, including a pump and a supply tank.

It is among the objects of the present invention to provide a mounting, rigid, and of simple structure and design, for an assembly including a water pump and its driving member, and a supply tank with which the water pump is connected.

Another object is to provide a support upon which the above mentioned assembled device may easily be mounted, even though variations exist in the length of the connecting pipes.

Further objects and advantages of the present invention will be apparent from the following description, reference being had to the accompanying drawing, wherein a preferred embodiment of one form of the present invention is clearly shown.

In the drawing:

Fig. 1 is a view in elevation looking into the open end of the horseshoe shaped base;

Fig. 2 is a section taken along the line 2-2 of Fig. 1; and

Fig. 3 is a section taken along the line 3-3 of Fig. 1.

Referring to the drawing, the numeral 20 designates a platform provided with feet 21 apertured to receive the clamping bolts 22 provided with clamping nuts 23.

Upon the platform 20 are supported the pump 24, the operating member 25 and the driving motor 26. A belt 27 drivingly connects the motor with the flywheel of the operating member 25. The pump is connected with a cylindrical storage tank 28 by means of a pipe, including the horizontal portion 29 and the vertical portion 30, the former being connected with the tank, the latter with the pump outlet port. The pipe, including portions 29 and 30 rigidly, operatively connects the pump with the storage tank.

A horseshoe shaped base 35 has a curved portion, of a contour similar to the contour of the cylindrically shaped tank 28. The base 35 comprises L-shaped walls, the hori-

zontal wall having the tank and the feet of the platform slidably supported thereon when said elements are first placed on the base. After being placed on the base, the assembled platform and tank are moved toward the closed end of said base until the tank 28 engages the curved portion of the vertical wall 36 of the base.

An elongated, horizontally disposed slot 37 is provided in the vertical wall of the base adjacent each end thereof. A clamping bolt 22 is inserted through each elongated slot and the non-aligned aperture of the foot 21 respectively, and tightening of the associated nuts 23, will rigidly clamp the feet of the platform in position on the base. The tank 28 being rigidly connected to the pump 24, supported on said platform, will therefore be held rigidly in engagement with the curved portion of the vertical wall 36, thus the tank is maintained in position on the base by the clamping bolts 22, which also hold the platform feet 21 rigidly on the base.

Variations in the length of the pipe portion 29 are compensated for by the provision of the elongated horizontally disposed slots 37.

Apertures 40 in the horizontal wall portions of the base are adapted to receive means for fastening said base to the floor or any other desired support.

In the foregoing it may be seen that applicant has provided a base of simple construction for a pumping apparatus and its associated supply tank, said apparatus as well as the tank being rigidly secured to the base by clamping bolts secured to the platform feet only.

While the form of embodiment of the present invention as herein disclosed, constitutes a preferred form, it is to be understood that other forms might be adopted, all coming within the scope of the claims which follow.

What is claimed is as follows:

Apparatus of the character described comprising in combination a storage tank, a pumping device, a conduit permanently and rigidly connecting the pumping device and tank, said conduit including a substantially

horizontal portion disposed adjacent the bottom of the tank, a base including a generally U-shaped member having an L-shaped cross section, one flange of which is vertically disposed and the other flange of which is horizontally disposed within the U, the bight of the U conforming to the contour of the tank, the tank resting on the horizontal flange and against the vertical flange within the bight, and adjustable means for clamping the pumping device to the vertical flange of the base to hold the entire apparatus in assembled relation through the thrust of the horizontal portion of said conduit transmitted through the tank against the vertical flange of said base.

In testimony whereof I hereto affix my signature.

HARRY G. FISHER.
